UNITED STATES PATENT OFFICE

113,233

DESIGN FOR A DOOR HANDLE

Walter Earl Manning, Jr., Chattanooga, Tenn.

Application November 4, 1938, Serial No. 80,949

Term of patent 3½ years

To all whom it may concern:

Be it known that I, Walter Earl Manning, Jr., a citizen of the United States, residing at Chattanooga, in the county of Hamilton and State of Tennessee, have invented a new, original, and ornamental Design for a Door Handle, of which the following is a specification, reference being had to the accompanying drawing, forming part thereof.

Figure 1 is a view in front elevation of a door handle, showing my new design, and

Figure 2 is a side elevation thereof.

I claim:

The ornamental design for a door handle, as shown.

WALTER EARL MANNING, JR.
